CIRCUIT BREAKER

Ludwig S. Walle, Lansdowne, Pa., assignor to
General Electric Company, a corporation of
New York

Application April 25, 1933, Serial No. 667,856

4 Claims. (Cl. 200—144)

My invention relates to circuit breakers, more particularly to circuit breakers of the type known as branch-circuit circuit breakers which provide the protective features characteristic of a fuse as well as the additional advantages of a manually operated switch, and has for an object the provision of a simple, reliable and inexpensive circuit breaker of this character.

Heretofore, branch circuit breakers have been provided with a thermal release arranged to trip the circuit breaker upon the occurrence of an overload, and with a manually operable handle for opening and closing the circuit independently of the thermal release. However, much is yet to be desired in such circuit breakers hitherto proposed to replace fuses because of the fact that the arc has been extinguished by means of magnetic blowouts and the like with resulting flame and arc gases. Inasmuch as branch circuit breakers as applied to panel-boards for the protection of lighting circuits, are called upon to interrupt currents of very considerable magnitude, as high as 5,000 amperes or more, when the breaker carries out the short circuit protective functions of a fuse, it will be apparent that a considerable quantity of arc gases are generated and that the flame of the arc is quite appreciable; these two features being undesirable for circuit breakers for household use. Furthermore, since the fuses which have hitherto been used accomplish this interruption of the circuit without spurts of flame, and without loud popping accompanying the interruption of an overload current of high magnitude, a satisfactory circuit breaker should also possess these advantages.

In carrying out my invention in one form thereof, I provide a circuit breaker which is capable of interrupting overload currents of large magnitude at lighting circuit voltages without the emission of flame or arc gases, and without noise, by enclosing the contacts in a sealed steel chamber of restricted volume. More specifically, I provide a mechanism for opening and closing the contacts with a snap action in response to movement of an operating handle and for opening with a snap action the contacts in response to overload current. The contacts move within the sealed metallic chamber so that when an arc is drawn between the separating contacts the gas pressure within the chamber increases quite rapidly. This pressure may be of the order of 1000 pounds per square inch. The resistance of the arc increases rapidly with pressure so that as the pressure is

built up the resistance becomes so great that the arc can no longer exist, and it is extinguished.

For a more complete understanding of my invention, reference should now be had to the accompanying drawings wherein I have shown diagrammatically in Fig. 1 a side view partly in section of a circuit breaker embodying my invention; Fig. 2 shows the parts of the circuit breaker of Fig. 1 just before the contacts are closed, while Figs. 3, 4, 5 and 6 illustrate an improved form of a circuit breaker embodying my invention.

Referring now to Fig. 1, I have shown my invention in one form as applied to a branch circuit breaker suitable for lighting circuits indicated by the conductors 10 and 11. The circuit breaker, mounted on an insulating base 12, comprises a frame 13 for the operating mechanism, a bimetallic thermal element 14 and an arc interrupter 15. The frame 13 has an upturned end 16 from which is pivotally supported at 17 an operating member 18 provided with an operating handle 19. The operating member 18 has an extension 20 to which is rigidly secured a rivet or projection 21 arranged to cooperate with notches 22 provided in a pair of parallel L-shaped links 26 between which the member 18 moves. One pair of adjacent ends 29 of the parallel links 26 are pivotally secured at 30 to the movable contact member 31 of the arc interrupter 15. The other ends 33 of the links 26 are provided with projections 34 which are engaged by adjacent ends of a pair of springs 37 which embrace the links 26. The other ends of the springs are secured to inwardly projecting ends 38 of the frame 13. It will be observed that the circuit represented by the conductors 10 and 11 may be traced from conductors 11 through the branch circuit breaker by conductor 40, thermal element 14, flexible conductor 42, movable contact member 31, stationary contact member 43 provided in the arc interrupter or compression chamber 15 and by conductor 44 to the conductor 10. The contact members 31 and 43 are constructed of an arc resistant material, for example silver molybdenum, but other arc resistant materials may of course be used.

The operating mechanism of the branch circuit breaker is trip free; that is to say, the operating handle 18, even though operated, cannot maintain a closed circuit if a current exists of sufficient magnitude to open the breaker. For example, in the operation of my invention it will be observed that the circuit breaker is normally closed after it has opened in response to a predetermined maximum current, the parts then being in the relative positions shown in Fig. 1, by 55

moving the operating handle 19 to the right, whereby the operating member 18 is rotated in a clockwise direction around its pivot 17 to bring its projection 21 into engagement with the notch 52 in the links 26 and thus move the links 26 a slight amount in a clockwise direction and also bodily downwardly. When the handle 19 strikes the end of the frame 38 the movable parts are in the positions shown in Fig. 2. A projection 48 extending from the links 26 is moved from the position shown in Fig. 1 downwardly beneath a latch 49 carried by the thermal element 14. The latch may of course be operated by means other than a thermal element. At this time the movable contact 31 has not engaged the stationary contact 43 to close the circuit. As soon, however, as the operating handle 19 is released the springs 37 rotate the links 26 about the projection 48 to operate the movable contact 31 into engagement with the contact 43 with a snap action, thus closing a circuit through the breaker. The springs 37 expend only a part of their energy in operating the contact 31 to the closed position. The remaining energy is at all times available for operating with a snap action the contact 31 to the open circuit position in response to overload or short circuit current. The floating links 26 in the final or closed circuit position are free of the operating handle. The links 26 as they free themselves from the handle 19 impart to the handle through the projection 21 an impulse which returns the handle towards the off position. As shown in Fig. 1, the handle is retained in an intermediate position by the engagement of the end 20 of the handle with the leaf spring carried on the frame. By moving the handle 19 from this intermediate position in a counter-clockwise direction, as viewed in Figs. 1 and 2, a projection 18a carried by the operating member 18 operatively engages the thermal element 14 to move it to release the latching projection 48. The springs 37 thereupon operate the movable contact 31 with a snap action to the open circuit position.

Assuming now that an overload occurs on the circuit represented by the conductors 10 and 11, the thermal element 14 is flexed in a clockwise direction to release the latching member 49 from the latching projection 48. The springs 37 thereupon cause the movable contact 31 to move toward the right as viewed in Fig. 1 with a snap action to the open circuit position shown in Fig. 1. As the movable contact 31 leaves the stationary contact 43, an arc is drawn between them. The arc interrupter 15 comprises a steel cylinder 53 within which a pair of kerosene-free fiber bushings 51 and 52 extend. I have found that kerosene-free fiber or an equivalent material is essential to the operation of my invention and deem its use in the arc chamber an important part of my invention. The steel or metallic cylinder and the insulating members are so arranged as to provide a sealed chamber of relatively small volume, such that the arc causes a rapid increase in air pressure in the chamber, the high air pressure exerting an opening force on the movable contact. This increase in pressure is due to the heating by the high temperature of the arc of the air within the chamber. The rise in pressure may be further accentuated by the heating of other gaseous fluids produced by the action of the arc on the air and the materials within the cylinder.

In order to produce a strong and rigid construction of the arc chamber, the bushings 51 and

52 are inserted into the ends of the steel cylinder. The ends of the cylinder are then swaged over the relatively narrow peripheral extensions 57 and 58 provided on the bushings. The steel cylinder 53 is in turn enclosed in a casing 60 of insulating material. The stationary contact member 43 has screw threads 61 provided at one end arranged to cooperate with a threaded member 62 forming a part of the conductor 44. The insulating bushing 51 permits a reciprocal longitudinal movement of the movable contact member 31, one end of which is always located in the chamber and the other end of which is always located outside of the chamber.

A leather sealing washer 65 is provided around the movable contact member 31, the washer being provided with an inwardly projecting cylindrical extension 66. Since a certain amount of metal vapor is produced when the circuit breaker interrupts a current of large magnitude, it is necessary to prevent this metal vapor from collecting on the movable contact member 31 where it may harden and interfere with successive operations of the circuit breaker. The leather washer with its inwardly extending projection tends to prevent this collection of the metallic vapor because of its wiping action on the movable contact member 31 and furthermore assists in maintaining a substantially air-tight connection around the movable contact member 31 by its cooperation with the contact member and the walls of the chamber. At the same time the leather washer provides for snap movement of the movable contact by the spring means by offering only relatively slight friction to such movement.

As I have stated, when an arc is drawn between the contacts 31 and 43, the air pressure within the chamber of the arc interrupter increases rapidly. The potential drop across the arc is not entirely dependent on the rise in pressure inasmuch as the cross sectional area of an arc is approximately proportional to the current. It is believed that the arc potential drop is approximately proportional to the inverse square root of the current. This characteristic of the arc, in addition to the rise in pressure in the chamber, causes a quick interruption of the circuit. Furthermore, since the rise in pressure depends upon the magnitude of the current interrupted, it will be seen that the greater the over-load current the more quickly will the pressure rise to a point where the arc resistance becomes so great that the arc can no longer exist. Obviously, the pressure within the chamber also exerts an opening force on the movable contact accelerating its speed of opening in proportion to the degree of pressure built up by the heat of the arc.

Of course, it will be understood that in order to reclose the circuit breaker it is only necessary to repeat the operations described in connection with Figs. 1 and 2.

Referring now to Figs. 3, 4, 5 and 6, I have shown what is believed at the present time to be the best form of an operating mechanism. This particular operating mechanism forms no part of my present invention, and it is described and claimed in a copending application Serial No. 667,855, filed April 25, 1933, Atwood, entitled "Circuit breaker" and assigned to the same assignee as the present invention.

A base 80 formed of molded insulation provides a support for the operating mechanism as well as for the arc interrupter 15. The arc interrupter or compression chamber 15 is inserted within an

enclosure 82 molded integrally with the base 80. The stationary contact 43 is provided with screw threads 61 engaging a threaded aperture in L-shaped conductor 44, the inner threaded end 84 of which is located within the molded enclosure 82, the other end of the conductor 44 extending through a slot 85 to form a terminal. The movable contact member 31 is mounted for reciprocal longitudinal movement into and out of engagement with the stationary contact 43. A washer 65 of leather or other suitable material is placed between the bushing 51 and a closure member 86 provided with a flange 87 arranged to engage the notched end 88 of the insulating enclosure 82.

10 The operating mechanism is supported from the base by means of a U-shaped frame 89. Extending at right angles from the upper ends of the legs of the frame are a pair of outwardly projecting extensions 90, which extensions are provided with notches 91 for engagement with projections 92 molded integrally with the enclosure 82. The frame 89 is secured by screws 94 extending through the base 80 in a position such that the portion 95 of the frame abuts the closure member 86 and maintains it securely in place. The frame, therefore, performs the double function of maintaining the closure 86 in place and supporting the operating mechanism.

15 The reciprocal vertical movement of the contact member 31 is obtained by means of a pair of over-center springs 98, which springs have their corresponding upper ends 99 carried by projections 100 secured on opposite sides of the operating handle 101. The opposite ends of the springs 98 are secured to a pin 102 extending through an aperture in the movable contact 31 near its outer end. The operating handle 101 is secured to an inverted U-shaped operating member 101a which in turn has its legs mounted on a pivot pin 104 carried by the upper ends of the arms of the U-shaped support 89. When the operating handle is moved from its left-hand position, shown in Fig. 3, to its right-hand position, shown in Fig. 4, the movable contact 31 is moved to and from its closed circuit position with a snap action. The reciprocal vertical movement of the movable contact 31 is insured by member 104a, comprising two parallel legs connected together by a mid-cross portion 104b. The upper ends of the legs 50 are mounted on the pivot pin 104, while their lower ends are pivotally secured to the pin 102. Since the lower end of the member 104a moves in a curved path about the pivot 104, the opening in the movable contact member 31 through which the pin 102 extends is elongated in a vertical direction, i. e., in the direction of the pivot pin 104, so that sufficient lost motion is obtained in a vertical direction to provide for freedom of movement of the pin 102.

55 In case of overload, a bimetallic thermal element 108 which is U-shaped as shown in Fig. 6 and connected in circuit with the switch contacts so as to be heated by the current passing through the breaker, is caused to flex away from a latch 109 to permit a quick opening of the circuit. It will be observed that the latch 109 is supported by a tripping member 110 which is mounted on the pivot pin 104. The member 110 has a notch 111 into which extends a rod 112 into abutting relation with the member 110. A compression spring 115 encircles the rod and has one end normally engaging a stop member 116 secured to the extensions 90 of the frame 89, while the other end is arranged to engage a member 117 secured to the

rod 112. The tripping spring 115 is shown compressed in Figs. 3 and 5, with the contacts closed as shown in Fig. 5. As soon as the thermal element 108 releases the latching member 109, it will be observed that the force exerted by the tripping spring 115 is applied to the member 110 at the notch 111. This force urges the tripping member 110 in a clockwise direction around its pivot 104. The end 120 of the tripping member 110 engages the connection 104b of the member 104a which it will be remembered is connected to the movable contact 31. The spring 115 in rotating the member 110 in a clockwise direction thus quickly operates the contact 31 to its open circuit position as shown in Fig. 4. A projection 15 110a of the tripping member 110 is located just below the extensions 101b and 101c extending from the operating handle 101. An opening 138 is provided in the extension 101c. The relative movement of the tripping member 110 from the 20 position shown in Fig. 3 to the position shown in Fig. 4 brings a suitably colored portion on the extension 110a into registering relation with the opening 138 so that an indication is given that the 25 circuit breaker has been tripped to its open position.

In order to close the circuit breaker after it has been opened by overload as just described, the handle 101 is first moved in a counter-clockwise direction from the position shown in Fig. 4. An 30 extension 125 formed integrally with the operating member 101a strikes a projection 126 on the tripping member 110 and thereby rotates the tripping member in a counter-clockwise direction until the latch 109 is again in the latched 35 position as shown in Fig. 3. The switch closing operation is then completed by operating the handle 101 in a clockwise direction to the position shown in Fig. 5. A second projection 127 formed on the operating member 101a strikes the 40 frame 89 at the point indicated by the reference numeral 128 and acts as a stop for the operating member.

While I have shown a particular embodiment of my invention, it will be understood, of course, 45 that I do not wish to be limited thereto since many modifications may be made, and I, therefore, contemplate by the appended claims to cover any such modifications as fall within the true spirit and scope of my invention.

50 What I claim as new and desire to secure by Letters Patent of the United States, is:—

1. An electric circuit breaker for interrupting currents of 5,000 amperes at lighting circuit voltages comprising a metallic cylinder, an insulating bushing secured to each end of said cylinder and forming therewith a gas tight circuit interrupting chamber, a stationary contact member extending through one of said bushings into said chamber, a coacting movable contact member 60 guided for reciprocal longitudinal movement within the other of said bushings into and out of contact with said stationary contact member, a packing gland including a fibrous member coacting with said last named bushing and said 65 movable contact to seal said interrupting chamber around said movable contact member against the escape of gas at high pressures during circuit interruption, said chamber having a relatively small volume such that the air entrapped at atmospheric pressures in said chamber is heated by the arc formed upon separation of said contact members to generate high gas pressures on the order of 1,000 pounds per square inch, whereby 70 currents of 5,000 amperes at lighting circuit volt- 75

ages may be interrupted without detrimental burning of said contact members.

2. A circuit breaker for interrupting currents of 5,000 amperes or more at lighting circuit voltages comprising walls of pressure resistant material forming a gas tight compression chamber, a stationary contact and a movable contact in said chamber, snap action operating means for said movable contact on the exterior of said chamber, said walls defining a chamber having a relatively small volume such that the air entrapped at atmospheric pressure in said chamber is heated by the arc formed upon separation of said contacts to generate high gas pressures on the order of 1,000 pounds per square inch, whereby said breaker is capable of interrupting currents of 5,000 amperes at lighting circuit voltages without detrimental burning of said contacts.

3. A circuit breaker for interrupting currents of 5,000 amperes at lighting circuit voltages comprising a metallic cylinder, an insulating bushing mounted in each end of said cylinder, an annular flange on each end of said cylinder engaging the periphery of the corresponding bushing, each of said flanges being swaged over the periphery of its bushing to form gas tight seals between said cylinder and said bushings and thereby forming with said cylinder a gas tight circuit interrupting chamber, a stationary contact member extending centrally through one of said bushings into said chamber, a coacting movable contact member mounted in the other of said bushings for reciprocal longitudinal movement, said cylinder and said bushings defining a chamber having a relatively small volume such that the air

entrapped at atmospheric pressure in said chamber is heated by the arc formed upon separation of said contacts to generate high gas pressures of 1,000 pounds per square inch or more, whereby said breaker is capable of interrupting currents of 5,000 amperes or more at lighting circuit voltages without detrimental burning of said contact members.

4. A circuit breaker for interrupting currents of 5,000 amperes or more at lighting circuit voltages comprising a metallic cylinder, a bushing made of insulating material mounted at each end of said cylinder and forming therewith a circuit interrupting chamber, a stationary contact member mounted on one of said bushings, a coacting movable contact member mounted in the other of said bushings and guided thereby for longitudinal movement, said bushings having relatively narrow peripheral portions tightly engaging the end walls of said cylinder, sealing means between said movable contact member and its guiding bushing for substantially precluding the escape of gas at high pressure from said chamber during circuit interruption, said cylinder and said bushings defining a chamber having a relatively small volume such that the air entrapped at atmospheric pressure in said chamber is heated by the arc formed upon separation of said contacts to generate high gas pressures of 1,000 pounds per square inch or more, whereby said breaker is capable of interrupting currents of 5,000 amperes or more at lighting circuit voltages without detrimental burning of said contact members.

LUDWIG S. WALLÉ. 35
